UNITED STATES PATENT OFFICE.

OTTO GEISLER, OF GLOVERSVILLE, NEW YORK.

PROCESS OF TREATING LEATHER.

SPECIFICATION forming part of Letters Patent No. 549,193, dated November 5, 1895.

Application filed April 11, 1895. Serial No. 545,362. (No specimens.)

To all whom it may concern:

Be it known that I, OTTO GEISLER, a citizen of the United States, residing at Gloversville, in the county of Fulton and State of 5 New York, have invented certain new and useful Improvements in Processes of Treating Leather, of which the following is a specification.

My invention relates to the treatment of 10 leathers which are required to be soft and elastic or stretchy, such as those used for the manufacture of gloves.

My object is to provide a bathing material, which will remove the lime and clean the 15 skins for the tanning process, so that the flexibility and elasticity required for gloves shall be secured and the skins be made to receive the coloring material perfectly without streaking or spotting. I accomplish this object by the use of sour whey as the bathing material, the curd and fatty substances being 20 removed therefrom, and the result is that the lime is not only completely removed, but the skins cleaned from other substances, which 25 would interfere with the tanning process and the subsequent coloring.

Heretofore great difficulty has been found in the bathing of leather, the lime or other material making the leather hard, and while 30 many attempts have been made to remove the hardness of the leather and make it flexible and soft by the use of many bathing compounds all, so far as I am aware, have been more or less objectionable and of doubtful 35 efficiency.

I have discovered that the leather may be made soft and pliable by subjecting the skins, after the ordinary liming process, to a bathing process, which consists in the use of a bath of lactic acid, using sour whey as the particular material, which is worked into the skins by the use of a drum or paddle-wheel, two to three gallons of the whey being used to one hundred sheep-skins, this quantity varying according to the size and thickness of the 45 skins. The length of time for the immersion and working of the skins will depend entirely upon the character and condition of the skins being treated and the strength of the whey. The skins are then again worked and washed 50 and the ordinary treatment continued.

What I claim is—

1. The process of bathing glove leathers consisting in subjecting the same, after the liming treatment to the action of sour whey, substantially as described.

2. The process of treating glove leathers consisting in subjecting the skins to the liming action; working and washing the same; immersing and working said skins in a bath 60 of sour whey and washing and working the skins again, substantially as described.

In testimony whereof I affix my signature in presence of two witnesses.

OTTO GEISLER.
